UNITED STATES PATENT OFFICE.

GEORGE A. ALSOPP, OF NEWARK, NEW JERSEY.

DESIGN FOR A FINGER RING.

60,949.

Specification for Design.

Patented May 16, 1922.

Application filed August 11, 1921. Serial No. 491,591. Term of patent 3½ years.

To all whom it may concern:

Be it known that I, GEORGE A. ALSOPP, a citizen of the United States, residing at Newark, in the county of Essex and State of New Jersey, have invented a new, original, and ornamental Design for Finger Rings, of which the following is a specification, reference being had to the accompanying drawing, forming part thereof.

The drawing is an edge view, and sets forth a finger ring showing my new design.

I claim:

The ornamental design for a finger ring, as shown.

GEORGE A. ALSOPP.
